UNITED STATES PATENT OFFICE.

CHARLES W. DENNIS, OF BROOKLYN, NEW YORK, ASSIGNOR TO METAL PACKAGE COMPANY, OF BROOKLYN, NEW YORK, A CORPORATION OF NEW YORK.

BOX.

1,205,977.

Specification of Letters Patent. Patented Nov. 28, 1916.

Application filed February 23, 1916. Serial No. 79,858.

To all whom it may concern:

Be it known that I, CHARLES W. DENNIS, a citizen of the United States, and a resident of Brooklyn, in the county of Kings 5 and State of New York, have invented certain new and useful Improvements in Boxes, of which the following is a specification.

My invention relates to the construction of ornamental boxes and particularly to a 10 box the surface of which is composed of paper or similar fabric.

The object of my invention is to provide a substitute for pasteboard boxes that shall be superior to the pasteboard box in appearance 15 as well as in strength and that may be cheaply constructed and may present a durable highly ornamental appearance.

One of the objects of the invention is to provide an ornamental box having a continuous 20 line of decoration or ornamentation at the edge or corner between the side of the body or cover and the top or bottom and in this respect the invention is designed as an improvement upon boxes having paper 25 surfaces ornamented by a line of applied gilt or metal surface paper pasted or applied as a continuous line on said corner or edge.

A further object of my invention is to 30 avoid certain objections incident to boxes having rounded corners when made of pasteboard.

In carrying out my invention I make the body or cover, either or both, out of sheet 35 metal constituting the base for the reception and application of a thin sheet of paper or similar fabric applied to the surface of the metal and made closely adherent thereto by means of glue or other cementing substance. 40 I also, by preference, construct the body and the cover, either or both, out of sheet metal formed or struck up in a die into a cup-shaped body without seam or joint and coated with paper or other suitable fabric 45 cemented closely to the smooth outer surface of said cup-shaped body.

My invention consists in the construction of box hereinafter described and more particularly specified in the claims.

50 Figure 1 is a side view of a box constructed according to my invention. Fig. 2 is a vertical section of the box when adapted to hold face powder. Fig. 3 is a plan thereof. Fig. 4 is a vertical section through one

side of the body of the box with the neck in place.

1 indicates the cover and 2 the body of the box. Each consists of a sheet metal base 3 as shown in the cross-section and each is, by preference, made by striking up or forming it into the shape desired out of a piece of sheet metal, so that it shall be free from joint or seam. The cup-shaped bodies forming the base for the cover and body of the box are of substantially the same dimensions so that when placed together their edges will come into meeting engagement.

The construction of the base from sheet metal is particularly useful in the case of boxes having rounded corners and avoids 70 the objection found in the case of rounded corner boxes made of pasteboard that they are liable to crack at the corner so as to mar their appearance to an extent making the same practically worthless. In my construction the rounded corner being of sheet metal and having the paper closely adherent to the surface thereof such difficulty is not experienced.

The sheet metal base 3 is provided with 80 a closely adherent coating of paper or similar material 4 cemented to the outer surface thereof in any desired manner and giving to the completed box the appearance, in all respects, of an ordinary pasteboard box excepting that, by reason of the smooth metal surface and freedom from joints in the sheet metal base at the corners or other places the outside surface of the box presents an extremely smooth appearance. Said paper 90 surface is, as shown, extended around the edge of the cup-shaped metal body and also, by preference, covers the entire inner surface of each sheet metal body or cup although the latter feature of the construction 95 is not necessary to the main purposes of my invention.

To insure that the edges of the two cups shall come into meeting engagement in the completed box, a "neck" of pasteboard or other material 5 is secured in the cup-shaped metal body 2 forming the body of the box. The paper, by extending around the edge of the sheet metal, assists in the formation of a good joint at the edge of the box and 105 cover.

In pasteboard boxes designed particularly for toilet articles, it is frequently de-

sirable to give to the box an increased ornamental appearance by means of a metal band or line of gilt or similar metal surface at the corner 7 of the top and sometimes also 5 the corner 8 of the box body. This I secure cheaply and in durable form by applying the paper coating in such manner as to leave a continuous line of the sheet metal exposed around the box at said corner or corners, 10 the metal so exposed being preferably treated before the application of the coating with a gilt or other metal lacquer. When the coating is made of thin paper the line of decoration thus afforded by the exposed 15 metal at the corner cannot be distinguished from the ordinary gilt line provided in pasteboard boxes by gilding the surface or applying a strip of thin metalized paper while, moreover, the decoration provided according to my invention is much more 20 durable than that afforded in the ordinary constructions of pasteboard boxes. Furthermore, by applying the cemented coating in sections so as to break the surface of the 25 coating along the corner 7, I avoid the difficulty experienced when the paper is applied as a continuous coating including said edge, and arising from the tendency of the weak paper coating to break at said edge so 30 as to produce an unsightly appearance.

As the invention is particularly useful for toilet powder boxes, I show the box as provided with a false bottom 10 within the same and a flexible bag-like partial wrap- 35 per 11 of paper or similar material secured at its lower edges to the bottom of the box and open at its top to allow removal of the powder in small quantities by powder puff.

40 Fig. 4 is a vertical section through one side of the body of the box with the neck in place and illustrates the way of fixing the neck whereby I secure a neat appearance and a close fit of the cover. The coating 45 of paper 4 upon the metal base 3 where it passes over the edge of the metal base, in-

stead of being extended down on the inside of the base, is extended up along the side of the pasteboard neck 5 after it passes over the metal edge and is cemented to the paste- 50 board neck. A glazed or other paper coating 12 of the pasteboard on the outside of the neck is extended down over the paper of the base to a line substantially coinciding with the metal edge of the base and is 55 cemented or pasted to said coating. This forms a double lock or fastening for the neck and leaves a very narrow ledge for engagement by the edge of the cover and leaves no pronounced line of division between the neck and base. It will be understood that the pasteboard body of the neck is cemented or pasted directly to the inner metal surface of the base thus securing it firmly below as well as above the line of 60 projection of the neck above the edge of the base.

What I claim as my invention is:—

1. An ornamental box constructed of a sheet metal base and a closely adherent coating of paper, the metal of the base being exposed along the edge formed by the intersection of the side and top or bottom to produce a continuous line of ornamentation. 70

2. In a metal box having an inserted pasteboard neck, the combination of a body having a metal base and a coating of paper cemented to said base and extending over the edge thereof and up for attachment to the pasteboard of the neck and a coating for 80 the pasteboard neck extending down over the edge of the base coating and cemented or pasted thereto as and for the purpose described. 75

Signed at New York in the county of 85 New York and State of New York this 21st day of February A. D. 1916.

CHARLES W. DENNIS.
